ATTORNEYS.

UNITED STATES PATENT OFFICE.

JAMES M. WALSH, OF MILWAUKEE, WISCONSIN.

NAME.

Application filed January 7, 1924. Serial No. 684,893.

To all whom it may concern:

Be it known that I, JAMES M. WALSH, a citizen of the United States, and resident of Milwaukee, in the county of Milwaukee and

5 State of Wisconsin, have invented new and useful Improvements in Hames, of which the following is a description, reference being had to the accompanying drawings, which are a part of this specification.

10 This invention relates to improvements in hames, and more particularly to the means for adjustably and detachably connecting the lower end portions of the hames together.

15 It is one of the objects of the present invention to provide hames having a chain for fastening the lower ends together in which means are provided for locking the chain to the hame against loss when the hame is 20 in open position.

A further object of the invention is to provide hames having means for adjusting the distance apart of the lower end portions of the hame members to fit collars of different sizes.

A further object of the invention is to provide hames in which the use of straps and buckles are eliminated and all of the adjustable parts are firmly held in position.

25 A further object of the invention is to provide hames in which all of the extra links permitting the adjustment of the hames are positioned within the tubular portion thereof.

30 A further object of the invention is to provide hames having a chain and lever hook adjustment in which the lever hook is locked in closed position against accidental opening.

35 A further object of the invention is to provide hames having means for very close adjustment which is but a fractional portion of the regular adjustment.

A further object of the invention is to 40 provide a hame construction, which is simple, strong and durable, and is well adapted for the purpose described.

With the above and other objects in view, the invention consists of the improved hame 45 construction and its parts and combination as set forth in the claims and all equivalents thereof.

In the accompanying drawing in which the same reference characters indicate the 50 same parts in all of the views:

Fig. 1 is a front view of the lower portion

of a pair of hames embodying the improved construction with the lower ends in disconnected position;

Fig. 2 is a similar view with the lower 60 parts adjustably connected, a lower portion of one of the hames being in section;

Fig. 3 is a sectional detail view of the lower end portions of one of the hames taken on line 3—3 of Fig. 1; and 65

Fig. 4 is an end view taken on line 4—4 of Fig. 2 of the hame member shown in said figure.

Referring to the drawing, the numerals 8 and 9 indicate the hame members which are 70

preferably formed of metal and are of U-shape in cross section at their lower end portions.

The forward lower portion of the hame member 8 is provided with a line of perforations 10 to form transverse bars 11 75

which are selectively engaged by a hook 12 positioned within the hame member and connected to one end of a chain 13 to adjust the distance apart of the lower end 80

portions of the hame members. The lower 85

end of the hame member 8 is formed with a cross shaped opening 14 which is of a size to permit the free movement of the chain therethrough with the exception of the hook 12 at the inner end of the chain and the 90

larger link 15 mounted on the outer end of said chain. Said larger link 15 is formed with an inner hook portion 15' intermediate its length which may be engaged by the 95

next link when it is desired to make an adjustment less than the adjustment provided by one of the links.

The lower end of the other hame member 9 is bifurcated and of hook shape as indicated by the numeral 16 and between the 95

said hook portions a hook lever 17 is interposed and fulcrumed on the pin 18. The hook portion 17' of said hook lever is curved to correspond with the hook portions 16

of the hame member 9 so that when the 100 handle part of the lever is in closed position, as shown in Fig. 2, the hook portions will register with each other. The lower end

portion of the lever hook is formed with a flat face 19 which is engaged by the free end of a flat spring 20 and yieldingly held in locked position, as clearly shown in Fig. 105

2. Said spring is curved at one end and is mounted in a pocket 21 formed in the hame member 9 and firmly held in position 110

therein.

In assembling the parts, the spring is

snapped into the pocket 21 and the chain 13 is inserted through the cross shaped opening 14 and the hook 12 is then secured to the end of the inserted links and the chain is thus non-removably fastened to the hame member.

In use, the hook 12 is extended around one of the cross bars 11 to adjust the chain to the desired length and the lever hook handle 10 is swung downwardly to the position shown in Fig. 1 and the large link 15 is slipped over the handle and the handle is then swung upwardly to its closed position within the hame member. In moving upwardly, the link 15 will be carried over the hooked ends 16 of the hame member and on the inner side of the pivot pin and form an eye and thus relieve the lever hook of the strain. When the lever handle is swung 20 into the hame member, the strain of the chain will hold the hook lever in its closed position due to the strain being on the inner side of the lever, but in addition thereto the flat end of the lever hook is engaged by 25 the free end of the spring 20 which firmly holds the lever in closed position against accidental movement.

If it is desired to adjust the hames but a slight distance, the second link is hooked 30 over the hook part 15' of the large link and the desired adjustment will be obtained. With ordinary adjustments it is only necessary to engage the hook 12 with any one of the cross bars 11 to lengthen or shorten the 35 chain. While the hames are in open position the chain connection prevents the accidental loss of the chain.

From the foregoing description, it will 40 be seen that the hames are of very simple construction and are well adapted for the purpose described.

What I claim as my invention is:

1. The combination with hames having lower channeled portions and one of said 45 portions being in the form of a hook, a lever hook fulcrumed to said hook portion and having a handle portion which swings into the adjacent channeled portion, and a chain adjustably but non-removably connected to the other channeled portion and connectable to the hame hook portion by engagement with the hook lever.

2. The combination with hames having lower channeled portions and one of said 55 portions being in the form of a bifurcated hook, a lever hook fulcrumed between said bifurcated portions and having a handle portion which swings into the adjacent channeled portion to form a closure for the hook portion, the end portion of said lever hook being flat, a spring bearing against said flat 60 portion for yieldingly holding the lever hook in closed position, and a chain adjustably but non-removably connected to the

other channeled portion, the outer end of 65 said chain connectable to the hame hook portion by engagement with the hook lever.

3. The combination with a pair of hame members having lower channeled portions and one of said portions being in the form 70 of a hook, a lever hook fulcrumed to said hook portion and having a handle portion which swings into the adjacent channeled portion to register its hook portion with the hame hook portion, the other hame member being formed with spaced transverse bars, and a connecting member having a hook at one end which is engageable with any one of the bars for adjusting the length 75 of said connecting member but is non-removably connected to the hame member having the bars, the opposite end of said connecting member having a link through which the lever handle may be extended for removably connecting said member to the 80 hame hook portion.

4. The combination with a pair of hame members having lower channeled portions and one of said portions being in the form 85 of a hook, a lever hook fulcrumed to said hook portion and having a handle portion which swings into the adjacent channeled portion to register its hook portion with the hame hook portion, the other hame member being formed with spaced transverse bars 90 and with an opening at its lower end, and a chain extending through said end opening and having a hook at its inner end which is engageable with any one of the bars for adjusting the length of the chain portion extending 95 out of the hame member, the opposite end of the chain having a link through which the lever handle may be extended for removably connecting said link to the hame hook portion, said chain hook 100 and link being of greater size than the end opening to prevent separation of the chain 105 from the hame member.

5. A pair of hame members, one of which is provided with a lower channeled bar portion having openings forming spaced transverse bars, and a chain having a hook non-removably positioned within the channeled portion which is engageable with any one 110 of said bars for adjustably connecting the end portions of the hame members together.

6. A pair of hame members, one of which is provided with a lower integral channeled end portion provided with a line of spaced openings forming spaced transverse bars, the 115 end portion of said channel being closed to form an eye, hame connecting means extending through said eye, and a member on said hame connecting means engageable with the transverse bars and non-removable through 120 said eye.

In testimony whereof I affix my signature.
JAMES M. WALSH.
